UNITED STATES PATENT OFFICE.

ISAAC A. SCHWARZ, OF PHILADELPHIA, PENNSYLVANIA, ASSIGNOR TO HIMSELF, AUGUSTUS A. LAZARUS, AND BENJAMIN LIPPER, OF SAME PLACE.

DESIGN FOR A DRESS-TRIMMING.

SPECIFICATION forming part of Design No. 21,578, dated May 24, 1892.

Application filed April 30, 1892. Serial No. 431,363. Term of patent 3½ years.

To all whom it may concern:

Be it known that I, ISAAC A. SCHWARZ, a citizen of the United States, and a resident of Philadelphia, Pennsylvania, have invented a new and original Design for a Dress-Trimming, of which the following is a specification.

My design is fully shown in the accompanying drawing, which represents a face view of the trimming.

The design comprises the central tape-like band or ribbon *a*, beyond each edge of which project arch-like figures *b*, each composed of an outer cord loop and an inner cord loop, narrow bands *d* extending along these arch-like figures below the crowns of the same. A cord

f is carried back and forth across the central band *a* from the bases of the figures *b* along one edge of the same to the bases of the figures *b* along the opposite edge.

I claim—

The design for a dress-trimming, substantially as described, and as shown in the accompanying drawing.

In testimony whereof I have signed my name to this specification in the presence of two subscribing witnesses.

ISAAC A. SCHWARZ.
